UNITED STATES PATENT OFFICE.

HUGO R. SWANSON, OF BROOKLYN, NEW YORK. ASSIGNOR TO TRIANGLE KAPOK MACHINE CORPORATION, OF NEW YORK, N. Y., A CORPORATION OF DELAWARE.

FIBER-TREATING MACHINE.

Application filed November 26, 1927. Serial No. 235,767.

This invention relates to fiber treating machines.

One of the objects of this invention is the provision of a fiber treating machine and its associated system having a safety explosion pipe thereon to permit of the release of abnormal pressures to a point of safety.

A further object of this invention is the provision of an aeration tank and its associated elements which is adapted for cleaning cotton linters, kapok, felt fibers and the like for the purpose of removing dust and seeds therefrom.

A further object of this invention is the provision of the combination with an aeration tank and a closed circulatory system for treating fibers of means for receiving the accumulated dust in the aeration tank upon the creation of a back pressure in the system when for instance the feed hopper is opened.

A further object of this invention is the provision of a system of the above type which permits of the automatic removal of dust from the aeration tank with each feeding operation.

This and many other objects are sought by means of the invention.

This invention resides substantially in the construction, combination, arrangement and relative location of parts as will be more fully pointed out hereinafter.

Referring to the drawings--

Figures 1 and 1^A taken together represent a side elevational view of the apparatus of this invention showing the picker partly in cross section.

Figs. 2 and 2^A when taken together represent a top plan view of the system with some parts broken away.

Fig. 3 is a vertical cross sectional view of the top portion of the aeration tank.

Fig. 4 is a cross sectional view taken on the line 4-4 of Fig. 3.

Fig. 5 is a detail view of the picker showing the driving gears.

Fig. 6 is a vertical cross sectional view of the picker.

Fig. 7 is a vertical cross sectional view of the picker taken at right angles to the view in Fig. 6.

Fig. 8 is a perspective view of the leaf valve used in the pipe connecting the tank with the dust receptacle, and

Fig. 9 is another view of the valve showing some parts in cross section.

This invention in general relates to a system such as shown in the copending application of Kiliaen M. Van Rensselaer and myself Serial No. 176,938, filed March 21, 1927.

In the treatment of fibers in preparation for use in mattresses, cushions, and the like, it is necessary to break up the fibers from a matted, packed form to a loose, fluffy condition and at the same time to remove therefrom all dust and foreign materials such as, for instance, seeds in the case of those fibers which contain them. It is usual to provide some form of aeration tank connected to a closed circulation system in which is connected a blower for moving the fibers through the system. In the use of such systems it has been found that whenever the flow of material is interrupted for any reason, such as when the inlet pipe to the blower is opened for the receipt of fresh material, a back pressure is created which forces the dust collected in the aeration tank from the tank at any available openings. This is, of course, undesirable and this invention has to do with an attachment for the aeration tank to receive this dust. In the arrangement of this invention the dust in the tank which has to be periodically removed therefrom is automatically ejected from the tank to a receptacle at each feeding operation.

For a better understanding of the invention reference is made to the drawings in which 1 represents the floor or support for the apparatus and 2 a wall or partition, as for instance the wall of a building. The tank is shown generally at 3 and is provided with a clean out door 4 for access to the interior. Near the bottom thereof is a screen 5 supported in an inclined position over a removable drawer 6 so that the heavier particles of dirt and seeds from the fibers are permitted to fall therethrough into the drawer from which they may readily be removed from the tank. The top of the tank is provided with a screen 8 which is enclosed by a casing 7 to provide a separate chamber at the top of the tank and in communication therewith.

An outlet pipe is connected to the tank near the bottom thereof and is provided with a hopper 11 which has a hinged cover 12 through which fresh material may be fed into the system. The pipe 10 passes to and through the picker 13. The outlet of the picker is connected by the pipe 17 to the inlet of the blower 18. A by-pass 16 connects

the pipes 10 and 17 so that the material may be passed around the picker when desired. Valves 14 and 15 are arranged so that the by-pass may be opened or closed as desired.

5 The outlet of the blower 18 is connected through the pipes 19 and 21 to the top of the aeration tank. An inclined deflector plate 9 is mounted adjacent the opening where the pipe 21 connects to the tank 3 to deflect the fibers downwardly into the tank. A valve 100 is provided at the junction of pipes 21 and 19 which is operated by means of the lever 22 and the foot lever 25 which is connected thereto by means of the wire 24. A spring 23 connected to one end of the arm 22 maintains the valve normally in such a position that material passes from pipe 19 to pipe 21. When it is desired to fill a mattress casing for instance it is connected to the delivery end 20 of the pipe 19 and by depressing the foot lever 25 the valve operated by lever 22 swings upwardly to close pipe 21 and permit the passage of the fibers to the outlet 20 and into the casing.

25 A pipe 22' extends from the chamber or above the screen 8 through the valve 23' and into a small closet 24' which contains a dust receiving receptacle 25', such as for instance a bag. Another pipe known as an explosion pipe is shown at 26 and extends from the tank 3 to some point of safety, as for instance through the wall of the building. Communication between this pipe and the tank is normally prevented by means of a closure member 27 which may consist of a disc of thin metal which is adapted to be ruptured upon the creation of an abnormal pressure or an abnormal temperature within the tank 3. Under these conditions the material in the tank may be forcefully ejected to a point of safety, as for instance in the case of fire.

40 The leaf valve which is shown generally at 23 is in communication with the pipe 22 and is adapted to be opened by the air pressure in the pipe by the actuation of the weighted valves 30 which normally close the end of the pipe 22. This construction is clearly shown in Fig. 9. The blower 18 is driven through a belt 32 by means of an electric motor 31 and the picker 13 is driven through the belt 34 by means of the electric motor 33. The picker comprises two sets of rotating fingers 34 which are driven by means of the meshed gears 37 and 38 and the pulley 39.

45 The operation of the system is as follows: When the blower 18 is in operation the fibers to be treated are fed through the hopper 11 and are drawn through the pipe 10 and 50 through the picker 13 where they are broken up from their packed condition. The separated fibers then pass through the pipe 17, through the blower, through pipe 19, and into pipe 21 when the valve operated by 55 lever 22 closes off the outlet 20. The fibers

pass up through pipe 21 and strike the deflection plate 9 and fall down into the aeration tank. The fibers continue to circulate in the system in this manner until they are sufficiently cleaned and separated. The 70 heavier particles of dirt, etc. fall through the screen 5. When the fibers are sufficiently separated they may be by-passed around the picker 13 through the by-pass 16. When the fiber materials are in suitable condition 75 the valve operated by the arm 22 may be moved to close off pipe 21 and the fibers then fed through the outlet 20 to a mattress casing.

80 Whenever the hopper 11 is opened for the admission of fresh material a back draft is created within the tank 3 and when this occurs the lighter dust particles rise up through screen 8, pass through pipe 22 and through valve 23 into the dust receptacle 25. The 85 pressure created by the back draft causes the weighted leaf valves 30 to open downwardly (see Fig. 9) but as soon as the force exerted by the back draft is less than that exerted by the weights the valves 30 close 90 so that the dust in the receptacle 25 cannot return to the tank 3.

95 It will be apparent from the foregoing disclosure that the present invention provides a relatively simple and novel arrangement for carrying out the purposes set forth above. The opening and closing of the feed hopper door is the only operation necessary to clean the dust from the aeration tank. Thus it is apparent that the dust removal is automatic 100 and occurs with each feeding operation. It is apparent, however, that many changes in the detail of construction and relative arrangement of parts may occur to those skilled in the art without departing from the basic 105 idea of this invention. The invention should not, therefore, be limited by the disclosure given for purposes of illustration but rather to the field of the invention as defined in the appended claims.

110 What I seek to secure by United States Letters Patent is:

1. In a fiber treating machine, the combination with an aeration tank, a blower and a plurality of conduits arranged to form a closed circulatory system of a pipe connected to said tank and a closure in said pipe for normally cutting off communication between said pipe and tank, said closure forming the weakest point of said system whereby the 115 tank may be exhausted under abnormal conditions of heat and pressure without injury to the machine.

2. In a fiber treating machine, the combination with a tank and a closed circulatory system of a receptacle connected to said tank to receive dust ejected therefrom whenever a back pressure is created in said tank.

3. In a fiber treating machine, the combination with a tank, a closed conduit system 130

connected to said tank having a blower connected therein and a feed hopper in said system of a receptacle in communication with said tank to receive the dust in said tank 5 whenever a back pressure is created by opening said hopper.

4. In a fiber treating machine, the combination with an aeration tank having a screen near the top thereof to form a separate chamber, an outlet conduit and an inlet conduit connected to said tank, said conduits being connected to a blower, said inlet pipe being arranged to deliver the fibers being treated to said tank below said screen of a pipe connected to said separate chamber and a receptacle attached to said pipe to receive dust from said tank upon creation of a back pressure in said tank.

5. In a fiber treating machine, the combination with an aeration tank, a screen in said tank for providing a separate compartment near the top thereof, an outlet pipe connected to the bottom of the tank having a feed hopper therein, an inlet pipe connected to the 25 top of the tank and separated from said compartment by means of a deflector plate, a blower connected to said inlet and outlet pipes, a picker in one of said pipes, and an outlet connected to one of said pipes 30 and provided with a valve for isolating it therefrom, of a pipe connected to said compartment at one end and to a dust receptacle at the other through a leaf valve so that upon

the creation of a back pressure in said tank the dust therein will pass into said dust receptacle. 35

6. In a fiber treating machine, the combination with a tank, a closed circulation system including said tank of a dust receptacle connected to said tank through a conduit and a 40 valve in said conduit adapted to operate upon the creation of a back pressure in said system to establish communication between said tank and receptacle.

7. In a fiber treating machine, the combination with a tank, a closed circulation system including said tank of a dust receptacle connected to said tank through a conduit and a one way leaf valve in said conduit adapted to operate upon the creation of a 45 back pressure in said system to establish communication between said tank and receptacle.

8. In a fiber treating machine, the combination with a tank, a closed circulation system including said tank of a dust receptacle 50 connected to said tank through a conduit and a weighted leaf valve in said conduit adapted to operate to establish communication between said tank and receptacle whenever a back pressure of sufficient force to open said 55 valve is created in said system.

In testimony whereof I have hereunto set my hand on this 23rd day of November, A. D., 1927.

HUGO R. SWANSON.
